UNITED STATES PATENT OFFICE.

COSTI DE MEYER, OF BUDWEIS, BOHEMIA, AUSTRIA-HUNGARY.

PENCIL-HOLDER.

SPECIFICATION forming part of Letters Patent No. 377,194, dated January 31, 1888.

Application filed September 24, 1887. Serial No. 250,598. (No model.)

To all whom it may concern:

Be it known that I, COSTI DE MEYER, a subject of the King of Roumania, residing at Budweis, in the Province of Bohemia, in the 5 Empire of Austria-Hungary, have invented certain new and useful Improvements in Pencil-Holders; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 Referring to the drawings, Figures 1 and 2 show by inverted sectional elevations a pencil or crayon holder embodying my improvements. Fig. 3 is a detail view of the actuating and locking sleeve, and Fig. 4 is a like 20 view showing a slight modification in the construction thereof.

The invention relates to pencil, crayon, or pen holders of that class in which means are provided to retract the pencil, crayon, or pen 25 within its inclosing case or handle, and has for its object to provide a simple means whereby the said pencil, crayon, or pen may be projected out of its casing and locked into position for use and retracted again by simply 30 inverting the holder or handle.

To these ends the invention consists in the construction of the holder, and in combinations of parts whereby the desired results are attained, substantially as hereinafter described, 35 and as set forth in the claims.

In the drawings, A indicates the tubular casing or handle closed at one end and provided with a nozzle, a, at the other end. Within the handle is secured a guide-tube, B, 40 in which is formed a longitudinal slot, b, one end of which terminates in a lateral or horizontal branch, b', Figs. 1 and 2. Within said tube is closely fitted the pencil-carrier C, which may be of any desired construction and contains the pencil C'. The pencil-carrier C is 45 provided with a radial pin, c, that projects through the slot b of the guide-tube B and through or into a longitudinal slot, d', formed in a weighted or gravity sleeve, D, loosely 50 fitted and moving freely on the guide tube B. The slot d' has two inclined faces, d' d'', at the

opposite ends thereof, said inclined faces extending in reverse directions or from opposite sides of the slot, so that when either of said faces comes in contact with the pin c the 55 tendency will be to rotate the pencil-carrier C on its axis, the said pin being, as above stated, rigidly secured to said holder.

When the handle A is turned into the position shown in Fig. 1, with the nozzle a upward; 60 the pencil-carrier C will be retracted within its inclosing casing or handle and within the guide-tube B. When, on the contrary, the handle A is turned with the nozzle downward, as shown in Fig. 2, the sleeve D, as well as the 65 pencil-holder proper, will move together on the tube B until the pin c reaches the end of the slot b in said tube B. The inclined face d' now comes in contact with the pin c, and causes it to move laterally into the horizontal 70 branch b' of the slot and will there be held by the sleeve, the end of the pencil-carrier C projecting out of the handle A sufficiently for use of the pencil C'.

The sleeve D is of such a weight as to cause 75 it to move rapidly on tube B and exert such power on pin c as to impart the necessary partial rotation to the carrier C. To prevent the rotation of the sleeve D in tube B, when either of the inclined faces comes in contact 80 with the pin c it is provided with a tongue, d, that has a lip, d', Fig. 3, that fits into the longitudinal slot b of the guide tube B. The tongue d also serves to limit the inward movement of the sleeve D, and is of such a length 85 as to prevent the pin c from moving out of the open end of slot d' in said sleeve.

It is obvious that when the parts are in the position shown in Fig. 2, and the holder is inverted into the position shown in Fig. 1, the 90 sleeve D will move along tube B until the inclined face d' of the slot d' comes in contact with the pin c, when said pin will be moved laterally thereby out of the horizontal branch b' into the slot b, and both the sleeve D and 95 holder C will move together to the limit of their inward motion, determined by the tongue d of said sleeve, the carrier C being withdrawn into the handle, as shown in Fig. 1.

The form of the slot d' in sleeve D may be 100 varied, and a curvilinear slot, as shown in Fig. 4, may be formed in said sleeve, the effect on

the pin *c* being the same as above described; but as the sleeve is not free to move on the tube by reason of the frictional contact, as well as the resistance of the pin to the motion 5 of the sleeve, the weight of the latter should be sufficiently increased to overcome said resistance.

Having described my invention, what I claim is—

- 10 1. In a pencil-holder, the combination, with the tubular handle, a tubular guide secured therein and provided with an L-shaped slot, and a pencil-carrier fitted loosely in the guide and having a radial pin projecting through 15 the slot thereof, of a propelling device operating on the carrier-pin by gravity to move said carrier along and impart to it a partial rotation in the guide, substantially as and for the purpose specified.
- 20 2. In a pencil-holder, the combination, with the tubular handle, a tubular guide secured therein and provided with an L-shaped slot, and a pencil-carrier fitted and moving freely in the guide and having a radial pin projecting 25 through the slot thereof, of a tubular propelling device movable on the guide and op-

erating by gravity on the pin to propel the carrier along and impart to it a partial rotation in said guide, and a locking device to lock the tubular propelling device against rotation on the guide, substantially as and for the purpose specified.

3. In a pencil-holder, the combination, with the tubular handle, a tubular guide secured therein and provided with an L-shaped slot, 35 and a pencil-carrier fitted and moving freely in the guide and having a radial pin projecting through the slot thereof, of a tubular propelling device movable on the guide and operating by gravity on the pin to propel the carrier along and impart to it a partial rotation in said guide, a locking device to lock the propeller against rotation on the guide, and means to limit the movements of said propeller, substantially as and for the purpose 40 specified.

In testimony whereof I affix my signature in presence of two witnesses.

COSTI DE MEYER.
